UNITED STATES PATENT OFFICE.

JOSEF BEISLER, OF HAMBURG, GERMANY.

METHOD OF AND MEANS FOR ARTIFICIAL-TOOTH FASTENING.

Application filed January 21, 1927, Serial No. 162,654, and in Germany April 10, 1926.

This invention relates to a method of and means for securing artificial teeth on the gum or tooth remnant through the provision of a backing plate with which the porcelain portion of the tooth is connected in a manner to secure the parts against separation.

In carrying out the method, the porcelain section is provided with the usual securing pin which, in this instance, is terminally headed and the backing plate is molded about a cap designed to receive the headed end of the pin and also to receive cement in which the headed end of the pin is embedded. The cap, which as stated is molded into the backing plate, has an opening for the reception of a pin which corresponds approximately in size with that of the headed end of the pin, such cap inwardly of the opening being of gradually increasing diameter to provide for the maximum cement reception and to insure a firm and complete grip of the pin.

The method and means is illustrated in the accompanying drawings, in which:

Figure 1 is a vertical sectional view showing a completed tooth.

Figure 2 is a face view of the rear plate.

In carrying out the method, the porcelain section *a* of the tooth is provided as usual with the securing pin *d*, the free end of the pin, for the purpose of the present invention, having an enlarged head *c*. The cap *f* is placed over the projecting end of the pin, this cap being of the form shown in section in Figure 1, that is having an entrance or opening *h* which corresponds approximately to the size of the head *c* of the pin, such cap inwardly of the opening being of increased diameter with a rounded closed outer end. The cap has a depth approximating the full projection of the pin beyond the porcelain section of the tooth.

The backing plate, which is modeled from wax or like materials, is pressed over the cap *c* against the porcelain section of the tooth *a*, thus embedding the cap in the backing plate model. The model or wax backing plate is then carefully withdrawn, carrying with it the cap *c*, and the model is used for a casting of the appropriate backing plate *b* in desired material, as gold or the like. In this casting, of course, the cap *c* is embedded in the backing plate material in proper position.

Following the formation of the backing plate with the embedded cap *c*, the cap is filled with cement, indicated at *g*, and the backing plate pressed against the porcelain section *a*, the cap, of course, being passed over the pin *d*.

The pin naturally tends to displace some of the cement and the latter will flow between the backing plate and porcelain section as an aid in securing the meeting faces of these sections together, this face binding being indicated at *j*.

Obviously, as shown in Figure 2, the backing plate may be provided with a plurality of caps *f* to receive a plurality of pins on the porcelain tooth section.

By this method, particularly in the use of the cap of the peculiar form described, it is apparent that even if the cement fastening tends to loosen, there is little liability of the porcelain section becoming wholly displaced, for the porcelain section can only be separated from the backing by the direct outward movement of the former and in order to permit such movement, the mass of cement must pass through the opening *h*, which, of course, is of less diameter than the cement mass in rear of the opening.

By the method described, the enlarged end of the pin may be said to rest in rear of a wedge-shaped mass of cement which cannot advance owing to the narrow outlet provided for it and hence the pin and, therefore, the porcelain section of the tooth cannot become separated from the backing plate.

What is claimed as new is:

1. The herein described method of securing a porcelain tooth section to a backing plate, consisting in molding into the backing plate a substantially spherical pin-receiving cap formed in line with the face of the backing plate with an opening of materially less diameter than the maximum diameter of the cap and providing in the porcelain section a pin having a head, arranged beyond the section, corresponding approximately in diameter to that of the entrance opening of the cap, then filling the cap with cement and forcing the headed pin into and beyond the entrance of the cap to displace a portion of the cement and cause said cement to fill the space between the entrance opening of the cap and the head of the pin in a mass which in all directions radially of the axis of the pin exceeds the similar dimension of the entrance opening to the cap.

2. A means for securing a porcelain tooth section to a backing plate, consisting in a substantially spherical pin-receiving cap having an entrance opening materially less in diameter than the maximum diameter of the cap, said cap being designed to be molded into the

backing plate with the entrance opening flush with the surface of the plate, a pin projecting from the porcelain section having a head substantially corresponding in diameter with that of the entrance opening of the cap, and a filling of cement between the head of the pin and the entrance opening of the cap, whereby the wall of the cap, by reason of its divergent relation with respect to the face of the

backing plate, maintains the filling of cement in the cap in advance of the head of the pin gradually convergent in all directions toward the entrance opening, to prevent the longitudinal movement of said cement under endwise pressure on the pin. 10

In testimony whereof I affix my signature. 15

JOSEF BEISLER.
